BOTTLE FILLING MECHANISM

Adolph J. Lippold, Milwaukee, Wis., assignor to
Cherry-Burrell Corporation, Milwaukee, Wis., a
corporation of Delaware

Application February 23, 1935, Serial No. 7,742

63 Claims. (Cl. 226—116)

This invention relates to improvements in bottle filling mechanism.

It is the primary object of the invention to provide a novel, improved, simplified, and easily cleaned bottle filler which, in large measure, is standardized so that the same parts may be used in the manufacture of bottle fillers of the gravity type or the suction type, as the trade may require.

More specifically stated, the several features 10 of the machine include as objectives the provision of novel bottle supports individually adjustable to and from the filling nozzles and self-locking in any desired position of adjustment; the provision of a novel and particularly strong light 15 organization of filler and vacuum pipes to support an annular series of bottle filling heads; the provision of an automatically operable liquid seal in the line through which milk entrained with the air used in vacuum filling is freed from the 20 vacuum line; the provision of a novel and improved float valve mechanism; the provision of a distinctive control for vacuum filling which is easily cleaned and may be so adjusted as to minimize frothing and waste; the provision of novel, 25 effective means for preventing overload and damage to the parts; the provision of a novel pump which not only provides oil under pressure but distributes the oil successively under full pressure to various bearings without danger of over- 30 load or failure of lubrication in the event of stop- page; the provision of a novel and effective means 35 of lubrication ensuring priming for the pump; and the provision of a general organization wherein the driving mechanism is concentrated, lubrication facilitated, and the moving parts re- 40 duced to a minimum, operation made easy, and the problem of assembly and disassembly for cleaning is reduced to a minimum.

The present application is concerned primarily 45 with the rotary filling machine. The lubricating system and pump are claimed in a companion application No. 90,099 filed July 11, 1936. The overload clutch is claimed in a companion application 50 90,100 filed July 11, 1936. The float valve is claimed in a companion application No. 90,101 filed July 11, 1936. The organization of the loading and unloading mechanism with reference to the turntable and capper is claimed in my companion application Ser. No. 174,582 filed November 15, 1937 and entitled Bottle filling apparatus.

In the drawings:

Figure 1 is a view of my improved machine as it appears partially in side elevation and partially broken away to a longitudinal vertical section.

Figure 2 is a plan view of the device shown in Fig. 1 with the capping head removed and the milk admission pipe cut away.

Figure 3 is a view partially in side elevation and partially in section showing one of the individually adjustable bottle supports.

Figure 4 is a view of the bottle support taken in section on the line indicated at 4—4 in Figure 3.

Figure 5 is an enlarged detail in perspective showing the bottle feeding to the filling rotor and the elevation of the bottle supports on the rotor. 5

Figure 6 is an enlarged detail view in perspective showing the star wheel for unloading the bottles from the rotor and showing the means for lowering the supports as they approach the 10 unloading device.

Figure 7 is an enlarged detail in section showing the primary driving connections to the machine and a portion of the lubricating system.

Figure 8 is a view of the driving pulley with 15 its front wheel broken away to a section exposing the overload mechanism.

Figure 9 is a schematic view of the driving connections.

Figure 10 is an enlarged detail in radial section showing one of the filler heads of the vacuum 20 machine illustrated in Figures 1 and 2.

Figure 11 is a view taken in the direction indicated at 11—11 in Figure 10 looking at the adjustable valve plate of the filler head. 25

Figure 12 is a detail in section showing a modified embodiment of the invention in which gravity filling is employed.

Figure 13 is a detail view in section through the capping mechanism which is an element of the complete machine. 30

Figure 14 is an enlarged detail view in axial section through the float valve mechanism.

Figure 15 is an enlarged detail view in end elevation of the pump and distributor mechanism shown in Fig. 11. 35

Like parts are identified by the same reference characters throughout the several views.

The general organization of the machine is the same whether the filling operation is conducted by gravity or by vacuum. This general organization most clearly appears in Figs. 1 and 2. There is a hollow base 15 housing the driving connections and preferably supported by suitable legs. At one end of that base is the bearing 16 for the turntable 17 which carries the individual bottle supports and the filling mechanism hereinafter to be described. 40

At one corner of the other end of the base 15 is a bearing 18 for the capper turntable 19, which is also provided with bottle supports and is assembled on a shaft 20 which carries a conventional capper head 21 vertically adjustable upon the shaft by means of a screw 22 journaled in an arm at the top of the shaft and the nut 23 carried by the capper head. 45

Spaced above the hollow base 15, at the level of the lower bottle supports, is a table 25 across which the bottles are loaded, unloaded, and transferred between the filling and capping mechanisms. A single conveyor 26 is flush with the edge 60

of the table and serves to supply empty bottles and remove filled bottles from the machine. It operates conventionally with reference to the loading star wheel 27 and the unloading star wheel 28. The transfer star wheel is shown at 29. A suitable bottle guide member 30 of the form clearly indicated in Fig. 2 has surfaces concentric with the axes of each of the three star wheels to co-operate therewith in guiding the movement 10 of bottles.

It is to be noted that the machine is assembled symmetrically with reference to a longitudinal center line through the turntable of the filler. This makes it possible readily to convert the 15 machine for either right or left hand operation. The capper may be interchanged with the idler pulley shown at 72 (Figs. 2 and 9); the conveyor 26 may be moved to cut across the lower corner rather than the upper corner as viewed in Fig. 2; 20 and the star wheels may simply be inverted upon their respective shafts to adapt them for operation in the other direction, the motor and its bracket being transferred to the other side of the base for such operation.

25 Throat mechanism is preferably provided to guide the bottles from the conveyor on to the table 25 and within the interdental pockets of the star wheel 27. In the absence of an appropriate throat mechanism the tip of a star wheel 30 tooth will occasionally engage the side of a bottle under substantially balanced conditions of pressure so that the bottle will be held to the guide rail or fence without tending to move either forwardly or rearwardly thereon. Ultimately it 35 may either be crushed or may cause breakage of the machine or may snap from its position with such force as to break itself or other bottles. In order to guard against these contingencies and at the same time to provide a throat which is 40 adjustable for handling bottles of differing sizes, I prefer to employ the mechanism shown in Fig. 2.

45 Fixed vertical pins are provided at 260, 261 and 262. Upon pin 261 is fulcrum the arm 263 which has spaced bottle engaging portions at 264 and 265 and an intervening depression. The bottle engaging head 264 of this arm stands out above a portion of the conveyor in a position such as to 50 force toward the star wheel bottles which are approaching on the conveyor.

55 As the bottle passes around the head 264 of the pivoted arm 263 the lateral motion given to it will be in a direction opposite to that of the adjacent portions of the star wheel. The bottle 60 will be thrust toward one of the star wheel pockets on a path such that it will be difficult, if not impossible, for the bottle to be caught by the end of the star wheel tooth. The arm 263 is yieldable under the thrust of the compression 65 spring 266 about its pivot 261 and this yielding movement is such that it will not only relieve a bottle of pressure but will tend to assure its firm engagement in the pocket. As the star wheel rotates, any bottle which might be caught on the head portion 264 of the arm 263 will be 70 pushed from said head portion into the adjacent recess in the arm and its slight advance will relieve the pressure momentarily and seat the bottle in the star wheel pocket in its proper position. It is the function of the second projection 265 on arm 263 to make sure that the bottle remains in the pocket when it is delivered by the star wheel against the guide arm 267 which terminates flush with the guide member 30 above 75 referred to.

Guide arm 267 is likewise pivotally mounted, being carried on fulcrum pin 260 and provided with a projecting finger at 268 engaged by compression spring 269 which, like compression spring 266, is on rod 270. 5

Carried by the fixed pin 261 is a boss 271 in which is threaded a screw 272 turned by crank 273. This crank is fixed in an adjusting lever 274 so that the rotation of the crank will oscillate the adjusting lever about the fixed pin 269. 10 This adjusting lever has an arm 275 carrying the spring guide rod 270 and another arm 276 which is mounted on rod 271 in engagement with the compression spring 278 by means of which its motion is yieldably transmitted to the throat 15 member 280 mounted on fulcrum pin 262.

It will be apparent that when it is desired to 20 adjust the machine to handle small bottles and to constrict the feeding throat accordingly, the crank 273 may be turned in a direction to move lever 274 counter-clockwise about fulcrum pin 260, thereby swinging arm 275 in a direction to push the spring guide rod 270 downwardly to the left as viewed in Fig. 2. By increasing the compression on spring 266 and correspondingly 25 increasing the compression on spring 269, this movement of the spring guide rod will result in shifting inwardly the free ends of lever arm 263 and guide arm 267 while at the same time shifting inwardly the free end of the throat member 30 280 on the opposite side of the conveyor. A reverse movement of the screw will adjust the parts in an opposite direction.

The arrangement just described is claimed in my companion application Serial No. 182,992 35 filed January 3, 1938.

The general organization above described may be used without change, both for gravity fillers and for vacuum fillers. The driving and lubricating connections which are likewise common 40 to both types of machines, will now be described.

The driving motor 40 is mounted on a slide 41 on bracket 42 on the outside of the base. The driving pulley 43 is preferably divided into two parts subject to the compression of a spring 44, 45 whereby the speed ratio may be varied somewhat by adjusting the motor slide 41 to force the belt 45 to a greater depth between the component parts of the pulley. The belt may be a thick flat belt with beveled sides, as shown in Fig. 1. 50 It drives a special pulley 46 on the main drive shaft 47 of the machine, the pulley being free to rotate on the drive shaft save for an overload clutch automatically releasable to prevent damage to the parts when overload occurs. 55

Made fast to shaft 47 (see Fig. 7 and Fig. 8) is a clutch plate 48 to which is pivoted a lever 49 having a finger 50 adapted in the position shown in Fig. 8 to receive driving thrust from a bolt 51 which holds cover plate 52 to the face 60 of the pulley. The lever 49 is normally held in this position by engagement of its pointed end in a notch 520 of a lever 53 which also has another notch 54 near its fulcrum. Lever 53 is also pivoted to the plate 48 and is subject to an 65 adjustable degree of pressure from compression spring 55 which tends to maintain lever 53 in such a position as to anchor the end of lever 49.

In the event of overload, the thrust of bolt 51 on the finger 50 of lever 49 causes the pointed 70 end 49 to subject lever 53 to a camming action which overcomes the compression of spring 55 and allows lever 49 to spring over into engagement with notch 54, thereby freeing finger 50 from bolt 51 and allowing the pulley to turn free. 75

If the machine is stopped, the overload clutch can readily be reset by means of a rock shaft 56 having an exterior hand crank at 57 and an interior crank pin 58 which is so located that it bears against the lever 49 in a direction to move that lever from notch 54 back to its original position in notch 52.

The power received by the main drive shaft 47 through the overload clutch from pulley 46 10 is delivered through a worm 60 of worm gear 61 to a vertical shaft 62 upon which the star wheel 28 is mounted. Angular adjustment of the star wheel on the shaft may be made by loosening the nut 63 which clamps the tapered star wheel hub 54 between the cones 65 on the shaft. Star wheels 27 and 29 are detachably engaged on pins 65 carried by rotors 66 and 67 respectively, which are similarly angularly adjustable on shafts 68 and 69. The freedom with which the star wheels 20 27 and 29 are detachable from pins 65 enables the operator readily to replace these star wheels when the machine is to handle a different size of bottle. Each of the star wheels 27 and 29 performs a positioning function in properly registering the bottle on one of the supports by which it is to be lifted. It is not necessary to replace star wheel 28, since this star wheel merely discharges the bottles on to a conveyor on which no particular registration is important.

30 A single chain 70 (Fig. 9) passes about a driving sprocket 71 on the vertical shaft 62 and thence passes over an adjustable idler sprocket 72 and a sprocket 73 on star wheel shaft 74, and a sprocket 75 on main turntable shaft 76, and a sprocket 77 on star wheel shaft 78, and finally over a sprocket 79 on the shaft 20 of the capping turntable. Thus all the vertical shafts are driven by a single chain from the worm gear 61 and shaft 62.

40 The lubrication of the machine is best illustrated with reference to Figs. 1 and 7.

The gear pump 80 is driven directly from the main drive shaft 47 and comprises a driving pinion 81 and a driven gear 82. The pump casing is 45 open at its bottom and immersed in the lubricant within a moat or wall 830, which prevents foreign matter in the sump 85 from reaching the pump intake.

The filler pipe 83 discharges into a box-like 50 reservoir casting 84 through which the main drive shaft 47 passes and in which the worm 60 and the worm gear 61 are located. The surplus overflowing from this reservoir falls into the sump 85. The level of lubricant in the sump 55 is kept sufficiently high so that the grit-free upper surface portions thereof pass over the margin of the moat 830 and reach the pump intake.

Such lubricant as enters the interdental spaces of the pump gear 82 is expelled from such spaces 60 by the displacement of the teeth of pinion 81 and flows through the pipe 820 to a filter or oil purifier 840 and thence back through pipe 850 into the hollow interior of the pump gear 82. This gear serves as a distributor for connecting the 65 pressure pipe 850 consecutively with each of the various lines 86 to the several bearings of the machine. These lines communicate with the interior of the casing through holes therein as shown in Figs. 7 and 15, in positions such that 70 the openings 860 in the distributing gear 82 of the pump register first with a distributing pipe on one side of the casing and then with a distributing pipe on the other side thereof. The dimensions of the openings are preferably such that 75 the distributing port of the gear will overlap the

leads to two consecutive distributing lines 86, as shown in Fig. 15, thus serving to equalize any excess of pressure which may have been occasioned in one of the lines due to the tightness of the bearing fed therefrom.

5 There is also a ball check relief valve at 87 which opens axially from the hub of the distributing pump gear 82, to release to the sump any excessive pressure in the lines or in the interior of the gear.

10 If the lines were connected in parallel in accordance with the usual practice, there would be an excess of flow of lubricant through those lines offering least resistance to such flow. By delivering the entire power of the pump consecutively to the various distributing leads substantially uniformity of flow to all leads is assured, and sufficient pressure is available to displace minor stoppages, such as would become aggravated, rather than displaced, if the lines were connected 20 in parallel from an accumulator.

Both the gravity and vacuum type fillers have turntables and vertical adjustable bottle supports which will now be described.

The turntable 17 of the vacuum filler shown in 25 assembly in Figs. 1 and 2 comprises a skirted member to which posts 90 are secured at intervals. Over each post is telescopically sleeved a tube 91 carrying a bottle support or table at 92. The several individual bottle supports 92 comprise a complete annular series about the skirted turntable 17.

30 Means is provided for fixing and releasing the position of vertical adjustment of each tube 91 and its support 92 with reference to the post 90. 35 An inclined notch 93 (Fig. 3) in the post retains a friction clutch roller 94 in such a position as to wedge between the post and the tube 91 to resist any downward movement of the tube upon the post while permitting free upward movement 40 thereof. This clutch roller is released from gripping engagement by a push rod 95 extending vertically through the post and provided at its lower end with a cam follower 96 engaged by compression spring 97 normally to hold the rod out 45 of the position of interference with the free clutching engagement of roller 94.

On the outside of each tube 91 is a roller 99 in 50 a position to be acted on by fixed cam surfaces during the rotation of the turntable. When the appropriate cam surface is engaged by the roller 99 the tube 91 and any bottle carried on its table 92 will be elevated to a height determined by the cam, and the roller 94 will act to maintain the bottle at the desired elevation. When it becomes time to release the bottle an appropriate 55 lowering cam is provided, but before the bottle 92 will descend it is necessary to disengage the clutch roller 94 by a further cam which acts on the follower 96 to operate the push rod 95 to thrust 60 the roller to an inoperative position. The push rods act on the roller also at the time the table is elevated, if desired.

The lifting cam is best shown in Fig. 5 at 100. It is pivoted to a supporting arm 101 and adjustably maintained at an elevation determined by nut 102 by means of a compression spring 103. Obviously the compression spring has sufficient strength to lift the adjustable support as well as the table thereon. During the rotation of the 70 turntable 17 successive rollers 99 of the bottle supports ride over cam 100, whereby the tubes 91 and tables 92 of the bottle supports are raised and locked by their respective clutch rollers in an elevated position as clearly shown in Fig. 5. 75

The cam shoe 104 may be used to operate the push rod 95 at this point if desired. As will hereinafter be explained, the raising of the bottles engages them with the filling mechanism to receive milk. They continue in milk receiving relation to the filler mechanism until the turntable completes a predetermined degree of rotation.

The lowering mechanism is best shown in Fig. 10 6. The relatively fixed bracket 105 pivotally supports a cam 106 which picks up the successive rollers 99 during rotation of the turntable, and has a downwardly extending surface 107 for lowering the bottle supports. A complementary 15 cam 108 tends to engage the rollers 99 from above in case they stick for any reason and fail to fall by gravity on cam 106. In the meantime the cam shoe 109 has engaged the follower 96 of the push rod which disengages the clutch roller and 20 permits the support to move downwardly on its post 90 under the influence of the cams 106 and 108.

A rod 110 passes through ears 111 and 112 on the respective cams 106 and 108 and enables a 25 compression spring 113 to act on both cams to permit a yielding movement thereof about their respective pivots from the positions predetermined by the adjustable stops 115 and 116 respectively.

30 The construction is such that the cams are very readily interchangeable with other cams for producing different heights of elevation. The bottles must always be received from the table 25 at a given elevation and, in case of a vacuum machine, 35 the height of the filler nozzle is fixed. Consequently, small bottles would have to be elevated higher than tall bottles. By reason of the fact that the bottles are raised and lowered at predetermined points by an interchange of the cams, 40 and by reason of the fact that the bottles automatically retain their adjusted position between such cams, it is possible to dispense with the elaborate adjustable cam track which would otherwise be required to retain the bottles in engagement with the filler. With the present 45 device the problem of adapting the machine for different sizes of bottles is a problem merely of changing the star wheels 27 and 29 and the lifting and lowering cams, and making a corresponding 50 adjustment in the height of the capping mechanism.

The resilient mountings of the several lifting and lowering cam elements as above described 55 avoid breakage in the event that one of the bottle support clutches fails to release, or slips from its proper position. It also avoids breakage in the event that a particular bottle carried by one of the supports acted on by these cams (particularly the raising cam 100) is oversize. Serious 60 damage might be done to the mechanism if it were not for the yielding of the cam. Obviously this advantage is inherent in a discontinuous cam since it is only necessary to make the lifting portion or the lowering portion independently 65 yieldable, thereby avoiding the complexity which would be involved in any attempt to make a continuous cam yieldable at only one point. If a continuous cam were made bodily yieldable in response to an oversize bottle the result would be 70 to release all of the normal size bottles from engagement with their coating filler heads, thus interrupting the filling operation.

The beginning end of the lowering cam 106 is extended below the position at which such cam 75 will normally pick up the cam follower 99 of each

successive bottle support. If the automatic clutch mechanism fails to hold, and a bottle support is dropped in the progress of the machine, the cam 106 will nevertheless pick up the dropped support and hold at the proper level for delivery 5 of its bottle in the normal manner. If the support should be stuck, however, the spring 113 would permit the cam to accommodate itself to the position of the support without destroying 10 the equipment.

In the capping mechanism the same posts 90 are attached to the turntable 19, and the same tubes 91 are sleeved thereon for the adjustable support of bottle tables 92. Since it is an easy matter, however, to raise and lower the entire 15 capping head to adjust the machine for handling bottles of different sizes, and since, moreover, the bottles are not to be retained for any great length of time in an elevated position, it is not necessary to lock the adjustable supports, and 20 the clutch rollers are omitted. A fixed cam is used as shown at 118 in Fig. 1. The rollers 99 are constantly supported and controlled by the fixed surface of cam 118 which raises the bottles to capping position and lowers them for discharge 25 from the capper by star wheel 28.

Where a gravity filler is used, as shown in Fig. 12, the height of the tank may readily be adjusted, and consequently there is no need for interchanging the cam surfaces. The length of 30 travel in elevated position is such, however, that the bottle supports can most conveniently be held by the clutch mechanism, and accordingly such mechanism is there employed.

In the construction shown in Fig. 12 the 35 sprocket 75 is the same as that which has been described. Instead of being mounted on a solid spindle 76, however, this sprocket is mounted on a tubular spindle 760 which carries at its lower end a bearing on which a nut 120 and an adjusting gear 121 therefor are mounted. A bevel pinion 122 is carried by a retractable shaft 123 for engagement and disengagement with the gear 121 subject to the control of a shifting lever 124. A crank 125 on shaft 123 enables the manual operation of the nut to raise and lower a spindle extension shaft 126 which is screw threaded at 127 in engagement with the nut. When the machine is in operation the shifting lever 124 is manipulated to disengage the gearing so that the 50 handle 125 will remain at rest.

The turntable 170, which is mounted on the tubular spindle shaft 760 carries vertically projecting pins 128 and 129 engaged by openings in a sleeve 130 connected with the extension spindle 126 upon which the milk tank 131 is mounted. The arrangement splines the tank to the turntable 170 to turn therewith while permitting a ready adjustment of the tank vertically with reference to the turntable either to adapt the machine to different sizes of bottles or to facilitate the removal of the tank for cleaning or repair. In the gravity type of machine the nozzles 132 are of a conventional construction which includes a valve opened by pressure of the bottle to permit the milk to flow by gravity from the tank into the bottle during such period as the bottle support maintains the bottle in engagement with the nozzle, or until the bottle is filled.

I shall now describe the vacuum filling mechanism.

Mounted on the turntable 17 (Fig. 1) is a milk chamber 135 to which milk flows through pipe 136 subject to the control of a special float valve 137. The milk pipe 136, below the detachable 75

coupling 138, terminates in a ported fitting 139 over which the hub portion 140 of the float 137 is sleeved for vertical movement as the float rises and falls. The float 137 is in the form of an inverted cup floated by air trapped therein above the surface of the milk. When the milk in chamber 135 reaches a sufficient level the rise of float 137 cuts off the supply.

A float valve of this sort is ordinarily subject to leakage. I have found it possible to avoid such leakage by providing the hub portion 140 of the float and the fitting 139 of the milk pipe with complementary tapered sides both above and below the ports of the fitting. As clearly appears from Fig. 14, the upper beveled seat is of greater radius than the cylindrical bearing surface, while the lower beveled seat is of smaller radius than the bearing surface. The dimensions are such that these seats are engaged simultaneously when the float reaches its extreme upper position, and tests have demonstrated the fact that there is substantially no leakage when the sleeve valve is supplemented by tapered valve seats on each side of the port as shown.

As the sleeve valve is moved downwardly by the float due to a decrease of milk level in chamber 135, the tapered valves leave their seats as shown in Fig. 14, and finally, the ports of the sleeve 140 register with the ports of the pipe fitting 139, thereby allowing the milk to enter chamber 135. To prevent such milk from entraining the air trapped in the float 137, I prefer to employ an annular baffle at 141 about the admission ports.

There is a closure 142 for milk chamber 135 which has a tapered seat on the top of the chamber, and hence is virtually airtight without requiring any clamp. The vacuum chamber 145 is held stationary while the chamber 135 and closure 142 revolve with the turret.

While any desired means may be used to hold the vacuum chamber 145 against rotation, I prefer a freely detachable connection from the support 1420 upon which the separating chamber 147 is mounted. An arm 1421 is mounted on the support 1420 and a link 1422 has its ends loosely engaged respectively in the arm 1421 and in the top of the vacuum chamber 145, as clearly appears in Fig. 2. By simply lifting up on this link it is freed from engagement with the vacuum chamber to permit this chamber to be removed incident to the opening of the milk chamber for the cleansing of the ports.

The outer periphery of closure 142 is channeled at 143 to provide an air passage in which vacuum is maintained through ducts 144, vacuum chamber 145, and vacuum pipe 146. The pipe leads through a baffled separating chamber 147 which is entered by vacuum pipe 148 leading to the intake of the vacuum pump 149. Any milk entrained with the air drawn through the pipe 146 is discharged in chamber 147 and passes through duct 150 into a removable receptacle 151 from which an overflow pipe 152 leads back to the milk chamber 135.

The receptacle 151 provides a liquid seal which enables the automatic return of milk from the separating chamber 147 through the pipe 152 without loss of vacuum. It will be noted that the pipe 150 from the receptacle 151 and the separating chamber is of substantial length, the separating chamber being located at a sufficient height to enable a column of liquid to be maintained in pipe 150 equal to the vacuum produced by the pump 149. The capacity of the receptacle

151 is so calculated as to provide in pipe 150 a column of milk of the necessary height. Thus, when the air pump 149 is started, the milk chamber 135 and pipe 152 being at atmospheric pressure and the receptacle 151 being initially filled with milk, the vacuum produced in the separating chamber 147 will draw the milk from receptacle 151 upwardly in pipe 150 to a sufficient height to provide a column which balances the vacuum produced by the pump. Thereupon any excess of milk return to pipe 150 from the separating chamber 147 will release some of the milk from the lower end of the pipe until receptacle 151 is again filled, whereupon the excess passes back through pipe 152 at atmospheric pressure to the milk chamber 135.

The individual filler heads are spaced at distances corresponding to the separation of the bottle supports 92. They are all mounted on a ring 154, the ring and several heads being spaced from the milk chamber by milk conduits 155 leading upwardly from the bottom of the milk chamber and air conduits 156 leading approximately horizontally to the beveled surface of the milk chamber which registers with the air passage groove 143 in the closure 142. The positions of the pipes are such as to have the effect of a truss in rigidly fixing the position of the ring and the filler heads with reference to the milk chamber and the turntable. It is particularly to be noted from inspection of Figs. 1 and 10 that the milk pipes 155 lead upwardly to their respective heads from the bottom of the milk chamber 135, while the vacuum pipes 156 lead horizontally from the respective filler heads to the flange of the milk chamber through which they communicate with ducts 144 and vacuum chamber 145. Thus the pipes to and from each filler head make a triangle with the adjacent wall portion of the milk chamber, and the filler heads are rigidly supported and braced by the pipes which serve them, no other mounting being necessary other than the ring 154 which interconnects all of the heads against lateral displacement.

The filler heads are best illustrated in Figs. 1, 2, 10 and 11. Each filler head comprises a block 160 having a beveled face at 161 upon which a plate-like valve 162 is pivoted at 163. The valve has two projecting posts at 164 and 165 whereby it is manipulated between its open and closed positions.

On its under surface the filler head 160 carries a nozzle 167 receivable into the mouth of a bottle 168. The heavy gasket 169 surrounds the nozzle to engage the rim of the bottle. The nozzle is provided with a milk duct 173 and a vacuum duct 171, both of which lead upwardly through the filler head toward the beveled surface 161. Immediately adjacent that surface the milk duct 173 communicates with a duct-like extension 172 of the milk pipe 155 through the filler head. The vacuum duct 171 leads to the face 161 of the filler head where it communicates with a groove 174 that leads to the duct-like extension 175 like the vacuum pipe 156 through the filler head.

The fact that the series of vacuum ducts includes groove 174 exposed to the surface 161, tends to create a vacuum under the valve plate 162 which holds the valve plate to the face 161 of the filler head. The valve plate is otherwise freely removable from its pivot pin 163 for cleaning. The cleansing of all ducts and pipes is facilitated by the fact that they open through the

face 161 of the filler head. The groove 174 regulates the degree of vacuum applied to the bottle, and if it were not an open groove in the face 161 of the filler head it could not be cleaned.

5 Duct 171 is of the smallest diameter practicable to receive a cleaning brush. Yet its capacity is more than ample and is, in fact, so great that following the completion of the filling operation the air admitted through hole 180 to break the 10 vacuum would be withdrawn so rapidly through pipe 156 as to occasion violent agitation on the surface of the liquid of the filled bottle. This situation is controlled by making the groove 174 very shallow to limit the capacity of the vacuum 15 line and thereby to restrict greatly the circulation of air following the filling operation. The area of groove 174 is sufficient to permit of proper filling and yet to prevent agitation of the milk. Being an open groove, it is readily cleaned without special equipment.

20 The upper end of pipe 155 is well above the normal level of milk in the chamber 135. Thus, no milk can flow from the chamber to the bottles except when the bottles are subject to partial 25 vacuum due to the withdrawal of air through the several vacuum pipes 156. It will be noted from Figs. 1 and 2 that just before the bottles are fed on to the filler turntable by star wheel 27, the post 165 of each successive valve plate encounters the fixed arm 177 on bracket 178. Before that time the valve plate has been in the position shown in Fig. 11 wherein an orifice 180 in the valve plate has registered with the milk duct 172 to break the vacuum in the milk duct, 30 thereby to prevent a flow of milk. The effect of the engagement between the arm 177 and the valve pin 165 is to adjust the valve plate counterclockwise to a position of registry with the inclined surface 161 of the filler head as shown in 35 Fig. 2. This pivotal adjustment in a counterclockwise direction as viewed in Figs. 2 and 11, has the effect of interrupting the communication of milk duct 172 with the atmosphere through the port 180. Therefore the continuous withdrawal of the air through vacuum pipe 156 is 40 effective through ducts 175, 174, and 171, to maintain a vacuum in the bottle through which milk will be induced to flow from the storage chamber 135 through pipe 155 and ducts 172 and 173 to the bottle. This flow will continue as the filling 45 turret revolves.

Obviously the time required to fill the bottle will vary according to the size of the bottle, and consequently for larger and smaller bottles a 50 larger and smaller proportion of the circular path of travel of the filling turret will be devoted to the filling operation. The filling operation may be interrupted at any point by adjusting the valve plate 162 to the position shown in Fig. 11, thereby admitting air through port 180 to the 55 milk tube 172 and destroying the vacuum in the milk tube. This prevents any undue surplus of milk from being drawn through the bottle and the air ducts to the separator 147 and being converted into froth.

In order adjustably to interrupt the filling operation as soon as the bottles of any particular size have been filled, I provide an angularly adjustable arm 182 (Figs. 1 and 2) which is mounted on a ring 183 adjustably held by clamp 184 in any desired angular position on the annular flange 185 of the vacuum chamber which is held stationary by retaining rod 1422, anchored to supporting post 1420, see Fig. 2. A finger 186 mounted on the end of the arm 182 is in a posi-

tion to strike the pin 164 of each successive filler head rotating therebeneath. The arm has a fitting 187 which is steadied on the ring 154 which connects the filler heads. In this manner the plate valve 162 is readily oscillated to break the 5 vacuum in the milk line and to stop the filling operation at any given point. Throughout the remainder of the angular distance through which the bottles move on the turntable before passing around star wheel 29 to the capper, atmospheric 10 air enters the port 180 in volume sufficient to supply the amounts withdrawn through ducts 171, 174, 175, and pipe 156. Any froth in the bottle will be withdrawn by the air during this time and will separate out in the separator 147. The final 15 level of liquid depends upon the depth to which plug 167 extends into the bottle and is determined by thickness of seal 169. Since location of port 180 at top of milk duct clears out the latter, there is no need to provide displacement 20 in the bottle by plug 167 to receive liquid dropping out when bottle is lowered, as is the case in conventional gravity valves as well as in some vacuum fillers.

25 Each milk pipe 155 with its associated ducts 172 and 173 leading to the mouth of the bottle constitutes an inverted U tube of which the pipe 155 is a relatively long leg and the duct 173 an extremely short leg. The vacuum relief afforded by communication of port 180 with duct 172 occurs at the highest point in this inverted U tube and the length of duct 173 is so short that after the port opens only a very small quantity of milk will continue to flow to the bottle. The remainder will flow back in pipe 155 to the level of the 30 milk in the float chamber 135.

35 Vacuum will continuously be applied through pipe 156 and ducts 174 and 171. Consequently the air admitted to the bottle through port 180 will continue the displacement of all milk in the 40 vacuum line 171, 174, 156 which may have reached such line up to the point of the opening of port 180. Any such milk will be driven through the vacuum line without frothing or bubbling or substantial aeration, this being very advantageous 45 from the standpoint of leaving the milk in condition for return to the float chamber through the separating system 147, 150, 151 and 152.

It is particularly to be noted that by merely unscrewing the couplings of the milk pipe 156, 50 vacuum pipe 146, and the return pipe 152, it is readily possible to remove the several concentric closures and to expose the milk chamber for cleaning. The float will be lifted off with the closures and will readily be accessible. The valve 55 plates are readily lifted off and, as above noted, all pipes are directly accessible through the beveled surface 161 of the filler head 160. Thus, all portions of the apparatus exposed to the milk may be cleaned with the utmost ease and accessibility, with operator standing on the floor.

55 The operation of the apparatus may be summarized as follows.

Empty bottles arrive on conveyor 26 and, according to their size, are fed by interchangeable 60 star wheels 27 on to the filler turntable which includes vertically adjustable bottle supports.

65 As the bottle is transferred to the support it is at the level of the table surface 25, but immediately thereafter, in the course of turntable rotation, the roller 99 of each support encounters the adjustable cam 100 which easily lifts the support to a sufficient height so that the rim of the bottle is firmly pressed against the gasket 169 of the filler head. Immediately prior to this 70

point the valve plate 162 has been adjusted to shut off communication between the atmosphere and the milk supply pipe 155. Therefore the vacuum produced by the operation of pump 149 is transmitted into the machine through pipe 146, and air is withdrawn from all of the several radial pipes 156 and from the bottles which are not yet filled.

This vacuum in the bottles causes milk to flow from the constant level chamber 135 upwardly through the distributing pipes 155 and into the bottles.

At the point of rotation of the turntable where the bottles have been filled, the vacuum in the milk supply pipe 155 is broken by adjusting the plate valve 162 to a position such that the port 180 registers with the milk pipe. Air is continuously withdrawn through the mouth of the bottle, however, until the bottle is again lowered from the filler head.

The lowering takes place when the roller 98 of the individual bottle support rides between a pair of lowering cams, and the push rod 96 which controls the supporting clutch is concurrently released to allow the support to move downwardly. When the support is moved to the level of the table surface 25, star wheel 29 transfers the bottle from the filler turntable to the capper turntable which has similar supports whereon the individual bottles are successively raised to the cappers. In the capper turntable, however, there is no means for locking the supports in an elevated position, and upon the completion of the capping operation the bottles are lowered once more to table 25 and discharged by star wheel 28 on to the outgoing end of conveyor 26.

The mechanism has been illustrated in Fig. 2, but need not here be described in detail, which adjustably provides for ejecting bottles in the event that a bottle of improper size is fed to the machine. If anything else goes wrong which obstructs the free operation of the apparatus, the overload clutch shown in Figs. 7 and 8 and heretofore described, will be effective to interrupt all drive to the machine.

The lubrication system is best shown in Figs. 1 and 7 and has been described in detail. It provides a fully enclosed means of lubricating all bearings without any possibility of polluting the milk stream or of exposing the lubricant to foreign matter.

If the gravity filler shown in Fig. 12 is used, the loading, filling, capping, and unloading, of bottles are exactly as heretofore described with the single exception of the fact that the filling valve nozzles are controlled by valves which operate in response to the pressure of the bottles thereon to enable the milk to flow by gravity instead of the vacuum flow system just described above.

In conclusion, reference is again made to the compact organization, the simplicity, the strength, and the cleanliness of the device herein disclosed.

I claim:

1. In a bottle filler, the combination with a bottle supporting member and a guide member having relatively converging clutch surfaces and being relatively reciprocable, of a clutch dog biased for frictional engagement between said surfaces, whereby to lock said members against relative movement in one direction, and a clutch releasing connection extending along said guide to a position for engagement with said dog and movable in a direction to release said dog, where-
75 by to permit relative movement between said

supporting member and guide member in said direction.

2. A bottle filling machine comprising the combination with a turntable provided with a series of guides, of bottle supports individually adjustable on said guides, clutch mechanism effective upon individual supports to maintain them at predetermined levels of adjustment on said guides, means operative in the course of turntable rotation for disengaging said clutch mechanism, and a lowering cam fixed adjacent the path of turntable rotation and provided with means engageable with successive supports to control the downward movement thereof, said lowering means comprising vertically spaced downwardly inclined surfaces and said supports having cam followers engageable between said surfaces, whereby the controlled downward movement of said supports is positively assured.

3. A bottle filling machine comprising the combination with a chamber and an annular series of filling heads, of a supply pipe leading to said chamber, means for maintaining a substantially constant level of liquid in said chamber below the level of said heads, a ring connecting said heads, and means supporting said ring and heads from said chamber comprising upwardly inclined pipes leading from said chamber to the respective heads, a closure for said chamber provided with vacuum line connections, and vacuum pipes from said closure to the respective heads and bracing the series of said heads and said ring from said chamber.

4. A bottle filler comprising the combination with a central chamber, of a closure therefor providing a vacuum chamber, a supply pipe leading to said first mentioned chamber through said closure and provided with a float valve for maintaining a predetermined level of liquid therein, an annular series of filler heads surrounding said first mentioned chamber above said level, pipes leading upwardly from said first mentioned chamber to said heads, and vacuum pipes from said heads to the vacuum chamber within said closure, said several pipes providing means for supporting and bracing said heads.

5. In a bottle filler, the combination with a nozzle receivable into a bottle, of a filler head provided with a bottle sealing gasket about said nozzle and having ducts opening downwardly through said nozzle to said bottle, other ducts communicating with the first mentioned ducts, and leading away from said head for supply and vacuum respectively, said several ducts opening through said head for the reception of a cleaning brush.

6. In a bottle filler, the combination with a nozzle receivable into a bottle, of a filler head provided with a bottle sealing gasket about said nozzle and having ducts opening downwardly through said nozzle to said bottle, other ducts communicating with the first mentioned ducts, and leading away from said head for supply and vacuum respectively, said several ducts opening through said head for the reception of a cleaning brush, and a single closure removably positioned on said head to cover the openings of all of said ducts.

7. In a bottle filling machine, a filler head having a beveled surface and a bottle engaging portion and provided with a vacuum duct opening from said surface downwardly through said bottle engaging portion, a second vacuum duct communicating with said first mentioned duct adjacent said surface and opening out of said head,

- 5 a first liquid duct extending downwardly from said surface through said bottle engaging portion, and a second liquid duct communicating with the first adjacent said surface and opening 5 out of said head, the angle of said surface being such that all of said ducts are directly accessible through said surface for cleansing.
8. In a bottle filling machine, a filler head having a beveled surface and a bottle engaging portion 10 and provided with a vacuum duct opening from said surface downwardly through said bottle engaging portion, a second vacuum duct communicating with said first mentioned duct adjacent said surface and opening out of said head,
- 15 16 a first liquid duct extending downwardly from said surface through said bottle engaging portion, and a second liquid duct communicating with the first adjacent said surface and opening out of said head, the angle of said surface being such
- 20 that all of said ducts are directly accessible through said surface for cleansing, together with a plate applied to said surface and adapted to be held thereto by vacuum in said vacuum ducts for sealing the openings of said several ducts to 25 said surface.
9. In a bottle filling machine, a filler head having a beveled surface and a bottle engaging portion and provided with a vacuum duct opening from said surface downwardly through said bottle 30 engaging portion, a second vacuum duct communicating with said first mentioned duct adjacent said surface and opening out of said head, a first liquid duct extending downwardly from said surface through said bottle engaging portion, and a second liquid duct communicating with the first adjacent said surface and opening out of said head, the angle of said surface being such that all of said ducts are directly accessible through said surface for cleansing, together with 35 a plate applied to said surface and adapted to be held thereto by vacuum in said vacuum ducts for sealing the openings of said several ducts to said surface, said plate being pivoted for annular adjustment on said surface and provided with an orifice adapted in one position of pivotal adjustment of said plate to register with one of said liquid ducts to break the vacuum therein.
10. A bottle filling machine comprising the combination with an annular series of filling heads and a liquid reservoir below the level of 40 said heads provided with pipes individually connecting it with the respective heads, of a vacuum chamber provided with pipes connecting it with the respective heads, filling nozzles on the respective heads, vacuum and liquid ducts opening through the nozzles of the respective heads and communicating with the aforesaid vacuum and liquid pipes, a valve surface on each such head having a port communicating with the liquid 45 duct therein, a valve plate removably pivoted to said surface and provided with an aperture registerable with said port in one position of pivotal adjustment of said plate, means for moving said plate to a position in which said aperture is out 50 of registry with said port, and means for subsequently moving said plate to register said aperture with said port.
11. A bottle filler comprising the combination with a turntable having vertically adjustable bot- 55 tle supports arranged in annular series, of a corresponding series of filler heads carried by said turntable, a liquid supply chamber mounted centrally on said turntable within said series of filler heads, a series of pipes from said supply chamber 60 to the respective heads, said heads being above

the level of liquid supply in said chamber, a series of vacuum pipes leading to the respective heads, said heads having bottle engaging portions and a beveled surface, and vacuum and supply ducts communicating with the respective pipes and opening to said surface and thence extending through said bottle engaging portions for communication with a bottle, and a valve means carried by each such head and controlling communication between said liquid ducts and the exterior 10 atmosphere for the relief of vacuum in the liquid ducts when the valve means is open.

12. A bottle filler comprising the combination with a turntable having vertically adjustable bottle supports arranged in annular series, of a corresponding series of filler heads carried by said turntable, a liquid supply chamber mounted centrally on said turntable within said series of filler heads, a series of pipes from said supply chamber to the respective heads, said heads being above 20 the level of liquid supply in said chamber, a series of vacuum pipes leading to the respective heads, said heads having bottle engaging portions and a beveled surface, and vacuum and supply ducts communicating with the respective pipes and opening to said surface and thence extending through said bottle engaging portions for communication with a bottle, and a valve means carried by each such head and controlling communication between said liquid ducts and the exterior 30 atmosphere for the relief of vacuum in the liquid ducts when the valve means is open, and means in the path of rotation of said turntable for opening and closing said valve means successively at predetermined intervals in the course of turn- 35 table rotation.

13. A bottle filler comprising the combination with a turntable having vertically adjustable bottle supports arranged in annular series, of a corresponding series of filler heads carried by said turntable, a liquid supply chamber mounted centrally on said turntable within said series of filler heads, a series of pipes from said supply chamber to the respective heads, said heads being above the level of liquid supply in said chamber, a series 45 of vacuum pipes leading to the respective heads, said heads having bottle engaging portions and a beveled surface, and vacuum and supply ducts communicating with the respective pipes and opening to said surface and thence extending 50 through said bottle engaging portions for communication with a bottle, and a valve means carried by each such head and controlling communication between said liquid ducts and the exterior 55 atmosphere for the relief of vacuum in the liquid ducts when the valve means is open, and means in the path of rotation of said turntable for opening and closing said valve means successively at predetermined intervals in the course of turntable rotation, each such valve means comprising 60 a plate pivoted on the beveled surface of the respective head and apertured for registry with the exposed end of a liquid duct in one position of angular adjustment of the plate upon said head.

14. In a bottle filling machine, a filler head 65 comprising a block with a beveled face, a filler nozzle receivable in the mouth of a bottle and provided with a gasket engageable with the bottle mouth for the sealing thereof, and a plate pivoted on the beveled face of the head and provided 70 with means for its oscillation thereon, said plate being apertured and said head being provided with separate vacuum ducts communicating with each other and leading to the said face and with liquid supply ducts communicating with each 75

other and opening to said face in a position such that the aperture of the plate will register with at least one of said ducts in one plate position and will be out of registry thereof with another plate 5 position.

15. Bottle filling mechanism comprising the combination with a central milk chamber and an annular series of filler heads, of means spaced from said chamber and mechanically connecting the heads of said series with each other, pipes 10 leading substantially rectilinearly from said chamber to the respective heads, and bracing means leading from each head substantially in the radial plane of the pipe leading to the respective head and diverging from such pipe substantially rectilinearly—for "in radial planes and substantially rectilinearly" to points on said chamber axially remote from the connection of said pipe therewith, whereby each bracing 15 means, and pipe with said chamber comprise a skeleton frame of triangular form constituting means by which said filler heads are supported and braced from said chamber.

16. In a vacuum type bottle filling machine, the combination with a liquid supply chamber, a filler head having means providing communication with said chamber, a vacuum line leading from said head, and means for withdrawing air from said vacuum line, of a separating chamber included in said vacuum line as a part thereof and arranged to effect separation from the air of liquid entrained therein, a pipe leading from said separating chamber with a substantial vertical component of direction, a liquid seal compartment adjacent the bottom of which said pipe opens, and a return conduit from the top of said compartment to said supply chamber, said supply chamber being at atmospheric pressure and said pipe having sufficient length to accommodate the full 40 height of the column of liquid which may be supported by the pressure differential between said supply chamber and said separating chamber.

17. In a vacuum type bottle filler, the combination with a vacuum line including a separating chamber, of a discharge pipe from said chamber having a substantial vertical component of direction, and a liquid trap having a discharge port at a substantially higher pressure than said separating chamber with the lower portion of which said pipe communicates, said pipe having a sufficient vertical height to accommodate a column of liquid suspended therein by the differential pressure between said separating chamber and the discharge port of said trap receptacle.

55 18. In a vacuum type bottle filler, the combination with a filler head having supply and vacuum ducts, of a supply chamber provided with means affording communication with a supply duct of said head, a vacuum chamber having means affording communication with the vacuum duct of said head, a separating chamber, a vacuum line leading from said vacuum chamber to said separating chamber, means for withdrawing air from said separating chamber, 60 whereby to create a partial vacuum in said line, said supply chamber being at a pressure materially in excess of that in said vacuum chamber, a drain pipe leading from said separating chamber in a downward direction, and a trap 65 movably connected with said drain pipe and with the lower portion of which said pipe communicates, the size of said trap and the vertical height of said pipe being sufficient to accommodate a column of liquid supported by the pressure differential created by said air withdraw-

ing means, and said trap having an overflow for the discharge of material displaced by the accumulation of liquids received into said drain pipe from said separating chamber.

19. Bottle filling equipment comprising the combination with a filler head having a readily accessible face, and a pair of ducts having spaced terminal openings through said face, of means applicable to said face providing a closure for said duct openings, said face and closure means 10 having complementary portions providing a shallow groove between said openings sufficiently restricted in capacity to limit flow between said ducts, said closure means being readily displaceable to expose said groove for the cleaning thereof. 15

20. In bottle filler equipment, the combination of a bottle filling head having a bottle engaging portion, an inclined face, a duct leading from said bottle engaging portion to an opening in 20 said face, and a second duct leading rearwardly from another opening in said face, said openings being spaced apart, of means including a closure for said openings movable with respect to said head for affording a predeterminedly 25 restricted communication between said openings.

21. Bottle filling equipment comprising the combination with a milk chamber and a milk supply pipe, of a bottle filler head having a 30 bottle engaging portion and an inclined face thereabove provided with a hole with which said pipe communicates, a vacuum pipe, said face having a second hole with which said vacuum pipe communicates, a vacuum duct terminating in a third hole of said face and leading thence downwardly through said bottle engaging portion of said head, a milk duct communicating with the first hole of said face and leading downwardly through the bottle engaging portion of 40 said head, and a closure adjustable upon the face of said head over the first, second and third holes thereof, said face and closure together providing mutually spaced surfaces constituting a restricted passage between said second 45 and third holes in said face, which passage is fully accessible upon the movement of said closure. 55

22. In a vacuum filler, the combination with an annular series of supports for containers to be filled and an annular series of filler heads, of a vacuum chamber substantially at the level of said heads, an independent supply chamber immediately below the vacuum chamber, means for maintaining a liquid level in said supply 50 chamber below said heads and the tops of the containers on said supports, and means connecting the several heads independently with the respective chambers, said heads each having ports individual to the respective chambers 60 opening toward said supports, whereby said chambers are in communication substantially solely through said heads and the containers beneath the respective heads. 65

23. In a vacuum filler, the combination with an annularly arranged supporting means for containers to be filled, of a cooperating annular series of filling heads each including a closure and having therewithin vacuum and supply connections, means peripherally spacing the several 70 heads, a supply chamber below the level of said heads and having means affording communication from said chamber to the supply connections of said heads, means for maintaining in said supply chamber a level of liquid below said 75

heads and the tops of said containers and a vacuum chamber mounted directly upon the supply chamber at substantially the level of said heads and having means affording communication with the vacuum connections of the several heads, said heads having separate vacuum and supply ports for communication with the respective containers.

24. In a vacuum filler, the combination with 10 annularly arranged supporting means, of a cooperating annular series of filling heads each including a closure and having therewithin vacuum and supply connections, means peripherally spacing the several heads, a supply chamber below the level of said heads and having means affording communication from said chamber to the supply connections of said heads, a vacuum chamber mounted directly upon the supply chamber at substantially the level of said heads 15 and having means affording communication with the vacuum connections of the several heads, a vacuum line leading from said vacuum chamber and including a separating chamber, a pipe depending from said separating chamber and having sufficient vertical extent so that the separated liquid therein will balance the vacuum to which said separating chamber is subject, means for subjecting said separating chamber to partial vacuum, and means for returning from said pipe 20 to said supply chamber the separated liquid.

25. In a vacuum filling machine, the combination with annularly organized supporting means, of a cooperating annular series of filler heads, means peripherally spacing said filler heads in 35 said annular series, each of said heads including a temporary receptacle closure and vacuum and supply connections, a supply chamber below the level of said heads having means affording communication between it and the supply connections of said heads, said last mentioned means comprising brace means upwardly inclined rectilinearly from a low portion of said chamber to the several heads, and a vacuum chamber mounted upon the supply chamber in 40 unitary connection therewith at substantially the level of said heads and having means affording mechanical support and a substantially horizontal communication between said heads and said vacuum chamber.

50. 26. A vacuum filler machine comprising the combination with a supply chamber, of a vacuum chamber mounted thereon in unitary connection therewith, an annular series of heads surrounding said chamber at substantially the 55 level of the vacuum chamber, a set of pipes extending substantially rectilinearly from lower portions of the supply chamber to the respective heads and providing mechanical support for said heads as well as communication between said heads and said supply chamber, a second set of 60 pipes extending substantially horizontally from said heads to the vacuum chamber and providing mechanical support for said heads as well as communication between said heads and the vacuum chamber, and supply and vacuum connections to the respective chambers.

70. 27. A vacuum filling machine comprising the combination with centrally disposed supply and vacuum chambers and an annular series of heads 75 about said chambers having correspondingly beveled faces, each such head comprising a closure and having supply and vacuum ducts opening downwardly through said closure and supply and vacuum ducts opening laterally toward said chambers, said chambers having means pro-

viding communication with the respective ducts, all of the several ducts opening through the beveled faces of the respective heads, and a closure for each head applied to its beveled face for completing connection between the several ducts. 5

28. In a vacuum filler, the combination of a 10 filler head provided with a temporary closure and having supply and vacuum ducts opening from the end of said closure to a predetermined surface of said head, said head also having supply and vacuum communication, ducts opening to the same surface, and closure means at said surface for rendering the several ducts directly accessible for cleaning and affording communication between the respective ducts for supply 15 and for vacuum.

29. In a vacuum filler, the combination of a 20 filler head provided with a temporary closure and having supply and vacuum ducts opening from the end of said closure to a predetermined surface of said head, said head also having supply and vacuum communication, ducts opening to the same surface, and closure means at said 25 surface for rendering the several ducts directly accessible for cleaning and affording communication between the respective ducts for supply and for vacuum, said closure means comprising an air relief valve for admitting air to one of said ducts.

30. In a vacuum filler, the combination of an 30 annular series of filler heads and means providing supply and vacuum connections to the respective heads, of valve means individual to each head for the admission of air to one of said connections to terminate the filling operation, and 35 means rotatable with respect to the several heads for automatically operating said valve means at a predetermined point in the relative rotation to determine that portion of such rotation in which filling occurs. 40

31. In a bottle filler, the combination with a turntable, of a supply chamber, a vacuum chamber, and an annular series of filler heads mounted thereon, means connecting the filler heads with the supply chamber and the vacuum chamber respectively, valves carried by the individual heads for admitting air to one of said means, said heads being above the level of the supply chamber, whereby to depend upon the application of vacuum to deliver material from the supply chamber to the heads, and valve operating mechanism with respect to which said turntable revolves, said mechanism being positioned in the path of successive valves for operating them in a direction to admit air to said means for interrupting the vacuum therein when the filling has progressed to a predetermined point. 50

32. In a vacuum filler, the combination with a turntable, of a supply chamber and a vacuum chamber mounted thereon and an annular series of filler heads having supply and vacuum connections to respective chambers rotatable therewith, each of said heads having a port communicating with one of said connections for interrupting the vacuum therein, and valve 60 means controlling the port, said heads being above the level of the supply chamber, whereby continued vacuum is essential to the continuance of the transfer of material from the supply chamber to the head, and relatively stationary 65 valve operating means with respect to which the several heads revolve, said valves having portions in the path of said means to be actuated thereby in a port opening direction whereby to terminate the filling operation. 75

33. In a vacuum filler, the combination with a series of filler heads and a valve actuating device mounted for relative movement, each of said heads having a closure, vacuum and supply ducts opening therethrough, and vacuum and supply connections to said ducts, and a valve mounted on each of said heads and including means for admitting air to one of said ducts for breaking the vacuum therein, the valve having an operator extending into the path of relative movement of said valve actuating means to be engaged thereby in a valve opening direction, together with a source of supply from which said supply connections lead, said source being below the level of said heads whereby to be dependent upon the vacuum for the delivery of material through the supply duct of said head, the admission of air through said valve terminating the delivery of material through said duct.

34. In a vacuum filler, the combination with a supply chamber and a vacuum chamber, of a temporary closure provided with supply and vacuum connections to the respective chambers, the supply chamber being below the level of the closure, and means providing a port opening into the supply connection above the level of material in the supply chamber, a valve controlling said port, means for bodily moving said closure, and means adjustable in the path of such movement for actuating said valve for the opening of said port, whereby adjustably to control the duration of a filling operation in the course of such movement.

35. In a vacuum filler, the combination with a supply chamber and a vacuum chamber, of means including a temporary receptacle closure providing a pair of ducts communicating with the respective chambers, the duct communicating with the supply chamber comprising an inverted U having a short leg terminating at said closure above the level of supply in said chamber, said temporary closure including valve means for admitting air to said supply duct at a point above the level of supply and between the supply chamber and the temporary closure, valve operating mechanism including means for the opening thereof and means for the closing thereof, and adjustable means whereby the time interval between the opening and closing of said valve means is adjustable for terminating the filling operation.

36. In a vacuum filler, the combination with a vacuum chamber and a supply chamber, of a filler head comprising a temporary closure for a receptacle to be filled and disposed above the level of material in said supply chamber, means providing a duct in the form of an inverted U having a short leg extended through said head and closure, and a longer leg extending into a lower portion of said supply chamber, valve means for admitting air into said duct adjacent its highest point, and duct means leading from said closure to said head to said vacuum chamber.

37. A vacuum filler comprising the combination with a supply chamber and a vacuum chamber, of an annular series of heads around said chamber having temporary closures for receptacles to be filled, each of said heads having supply and vacuum ducts extending through said closure, means providing communication between the top of the supply duct of each such head and a lower portion of the supply chamber, means providing communication between the top of the vacuum duct of each such head and the vacuum chamber,

and valve means mounted on each such head for controlling the admission of air to the top of said supply duct, whereby to break the vacuum therein and to discontinue a filling operation through said duct.

38. A vacuum filler comprising the combination with a supply chamber and a vacuum chamber, of an annular series of heads around said chamber having temporary closures for receptacles to be filled, each of said heads having supply and vacuum ducts extending through said closure, means providing communication between the top of the supply duct of each such head and a lower portion of the supply chamber, means providing communication between the top of the vacuum duct of each such head and the vacuum chamber, and valve means mounted on each such head for controlling the admission of air to the top of said supply duct, whereby to break the vacuum therein and to discontinue a filling operation through said duct, and mechanism relatively movable about said annular series of heads for mechanically actuating successive valve means to open position.

39. In a vacuum filler, the combination with a turntable and a supply chamber, a vacuum chamber and an annular series of filler heads mounted thereon, of work supporting means mounted on the turntable in association with the filler heads for holding thereto the receptacles to be filled, each filler head being provided with supply and vacuum ducts for communication with receptacles carried by said supporting means, a pipe connecting an upper portion of the supply duct of each filler head with a lower portion of the supply chamber, the upper end of said pipe being above the supply level in said chamber, means establishing communication between the vacuum ducts of the several filler heads and the vacuum chamber, valve means mounted individually on the respective filler heads for controlling the admission of air to the supply ducts thereof, and valve actuating mechanism including a part disposed in the path of rotation of said filler heads on said turntable and adapted to actuate successive valve means to open position whereby to discontinue the filling operation through successive filler heads at predetermined points in the rotation of the turntable.

40. A vacuum filler comprising the combination with a turntable, of a supply chamber mounted thereon, means for delivering liquid at a constant level thereto, a vacuum chamber mounted upon the supply chamber, an annular series of filler heads at substantially the level of the vacuum chamber and above the level of liquid in the supply chamber, each of said filler heads including temporary receptacle closures and vacuum and supply ducts extending upwardly therethrough, means providing communication between the respective ducts and the vacuum and supply chambers respectively, said means including supply conduits commencing below the liquid level of the supply chamber and leading to a point above such level, a valve means carried by each head for admitting air to the supply duct above the level of liquid in said supply chamber, whereby to break the vacuum therein, mechanism for automatically actuating said valve means in the course of turntable rotation, a vacuum line connected with the vacuum chamber through which air and liquid reaching such chamber are withdrawn therefrom, and means for separating the liquid from the air and for returning it to the supply chamber.

41. In a vacuum filler, the combination with a supply chamber comprising a receptacle provided about its margin with a seat, of a filler head having supply and vacuum ducts and conduits leading thereto through the wall and the seat of said receptacle respectively, and a closure fitted to said seat and provided with vacuum passages communicating through said seat with the vacuum duct of said filler head.
- 10 42. A vacuum filler comprising the combination with a supply chamber comprising a circular vessel having a tapered seat at its margin, of an annular series of filler heads about said level at substantially the level of said margin, each of said heads being provided with supply and vacuum ducts, pipes connecting the lower portion of said vessel with the supply ducts of the several heads, pipes connecting the seat at the margin of the vessel with the vacuum ducts of the several heads, and a closure for said vessel fitted to said seat and provided with vacuum passages communicating through said seat and said last mentioned pipes with the vacuum ducts of the filler heads.
- 15 43. A vacuum filler comprising the combination with a supply chamber comprising a circular vessel having a tapered seat at its margin, of an annular series of filler heads about said level at substantially the level of said margin, each of said heads being provided with supply and vacuum ducts, pipes connecting the lower portion of said vessel with the supply ducts of the several heads, pipes connecting the seat at the margin of the vessel with the vacuum ducts of the several heads, and a closure for said vessel fitted to said seat and provided with vacuum passages communicating through said seat and said last mentioned pipes with the vacuum ducts of the filler heads, a vacuum line connected with said 20 passages in said closure, a separating chamber in said line, a column leading downwardly from said separating chamber of a height sufficient so that the liquid therewithin will balance the vacuum in said line, and means for returning the liquid from said column to said supply chamber.
- 25 44. In a device of the character described, the combination with a turntable provided with individually adjustable work supports and filler heads engageable by the work upon the adjustment of the respective supports, cam means for adjusting the supports in one direction, means functioning independently of the cam means for maintaining the supports in their adjusted positions, and a second cam means for actuating the supports in the opposite direction, at least one of said cam means being resiliently mounted for yielding movement independently of the other.
- 30 45. In a device of the character described, the combination with a carrier and a series of filler heads carried thereby, of a corresponding series of individually adjustable work supports mounted on said carrier for movement toward and from said filler heads, cam means at a predetermined station adjacent the path of said carrier for lifting said supports to raised positions, means upon which said cam means is resiliently mounted, clutch means for maintaining 35 said supports in the positions to which they are adjusted by said cam means, a second cam means at a second station adjacent the path of movement of said carrier for determining the lowering movement of said supports, means for resiliently mounting at least a portion of said sec-
- ond cam means, and means for releasing said clutch means at said second station to permit the lowering of said supports.
- 40 46. In a device of the character described, the combination with a carrier and adjustable work supports, of means for raising said supports, a separate means individual to each support for maintaining it in raised position during the travel of the carrier, means for releasing the maintaining device at a predetermined station in the path of movement of the carrier, and means at said station for lowering each successive support, said last mentioned means comprising a cam follower on the support and a pair of spaced cams providing a downwardly inclined path for each successive cam follower, both of said cams being resiliently yieldably mounted and provided with springs normally maintaining their positions under pressure sufficient to operate said supports under normal conditions.
- 45 47. A bottle filling machine comprising the combination with turntable means providing bottle supports in an annular series, of a central chamber partitioned to provide liquid supply and vacuum compartments and mounted on said turntable, an annular series of filler heads disposed above the bottle supports in positions for registry with bottles on said supports, liquid supply means communicating with the liquid supply compartment therein, means regulating the admission of liquid through said supply means to said liquid compartment for maintaining liquid at approximately a given level, liquid pipes leading upwardly to the filler heads from points in the liquid compartment below said level, said filler heads being disposed above said level, and vacuum pipes leading from the filler heads to the vacuum compartment of said chamber, said liquid pipes and vacuum pipes constituting with said chamber skeleton frames of triangular form disposed on different radii of said turntable and upon which said filler heads are supported and braced mechanically from said chamber as well as connected for filling operation with the liquid and vacuum compartments.
- 50 48. A bottle filling machine comprising the combination with turntable means providing bottle supports in an annular series, of a central chamber partitioned to provide liquid supply and vacuum compartments and mounted on said turntable, an annular series of filler heads disposed above the bottle supports in positions for registry with bottles on said supports, liquid supply means communicating with the liquid supply compartment therein, means regulating the admission of liquid through said supply means to said liquid compartment for maintaining liquid at approximately a given level, liquid pipes leading upwardly to the filler heads from points in the liquid compartment below said level, said filler heads being disposed above said level, and vacuum pipes leading from the filler heads to the vacuum compartment of said chamber, said liquid pipes and vacuum pipes constituting with said chamber skeleton frames of triangular form disposed on different radii of said turntable and upon which said filler heads are supported and braced mechanically from said chamber as well as connected for filling operation with the liquid and vacuum compartments, together with an 55 nularly disposed means spaced from said chamber and connecting the several heads against relative lateral displacement.
- 55 49. A bottle filling machine comprising the combination with an annular series of filler heads,

each having first and second ports for liquid and vacuum respectively, of a vessel disposed centrally within said series, a first set of pipes leading from the bottom of said vessel upwardly to the filler heads and affording communication between the vessel and the first ports, a second set of pipes leading from the filler heads to an upper portion of the vessel and affording communication with the second ports, said pipes being rigidly anchored in the vessel and filler heads whereby the pipes constitute radially projecting skeleton frames for the mechanical support and bracing of the filler heads from the vessel, means constituting a removable partition for said vessel to segregate that portion thereof with which said first mentioned pipes communicate, said means providing a vacuum chamber having openings positioned to register with said second pipes, and vacuum and supply connections leading respectively to the vacuum chamber and to that portion of the vessel below said partition.

50. A bottle filling machine comprising the combination with a chamber having a lower liquid compartment and an upper vacuum compartment, of an annular series of multi-ported filler heads concentric with said chamber, a removable centrally ported closure for said chamber, liquid supply and air conduits entering said chamber through the port in said closure and leading to the liquid and vacuum compartments respectively, means for maintaining a substantially constant liquid level in said liquid compartment below the level of said filling heads, and means supporting said heads from said chamber comprising upwardly inclined pipes leading from said chamber to the respective filler heads, said pipes establishing passages between said liquid compartment and the ports in said filler heads respectively.

51. A bottle filler comprising the combination with a central atmospheric chamber, of a centrally ported hollow closure therefor removably sealed to the upper portion of said chamber, said ported hollow closure forming a ported vacuum chamber, a seal for said ported closure, means for withdrawing air through said seal from within said hollow closure, means for supplying liquid through said seal to said central chamber, an annular series of filling heads connected respectively to said chamber by upwardly inclined pipes, and means for maintaining a substantially constant level of liquid in said chamber below the level of said heads.

52. A bottle filler comprising the combination with a turntable having vertically adjustable bottle supports arranged concentrically in annular series, of a liquid supply chamber mounted centrally on said turntable and having a hollow centrally ported closure removably sealed to the open upper portion of said liquid supply chamber, an annular series of filler heads carried by said chamber, a series of supply pipes from said supply chamber to the respective heads, said heads being above the level of the liquid supply in said chamber, a series of vacuum pipes leading to the respective heads, said heads having bottle engaging portions, vacuum and supply ducts communicating with the respective pipes and extending through said bottle engaging portion for communication with a bottle, and a valve means carried by each of said heads controlling communication between said liquid ducts and the exterior atmosphere for the relief of vacuum in the liquid ducts when the valve means is opened.

53. In a vacuum filler, the combination with

a turntable having supply and vacuum chambers centrally mounted on the turntable to rotate therewith, of a filler head constituting a temporary receptacle closure and disposed wholly above the level of the supply chamber and provided with supply and vacuum connections to the respective chambers, means supporting said filler head from said turntable, said filler head having a port opening into the supply connection above the level of material in the supply chamber, and a valve controlling said port for admitting the atmosphere to the supply connection when the valve is open.

54. In a vacuum filler, the combination with a turntable, of a supply chamber centrally mounted thereon, a vacuum chamber on the turntable above the supply chamber, a filler head provided with means supporting it from the turntable and including a temporary receptacle closure having a pair of ducts in operative communication with the respective chambers, the duct communicating with the supply chamber comprising an inverted U having a short leg terminating at the filler head above the level of supply in said chamber, and valve means carried by the filler head for admitting air to said supply duct at a point above the level of supply and between the supply chamber and the temporary closure, and means for the actuation of said valve means during turntable rotation.

55. A bottle filler comprising the combination with means providing a liquid supply chamber and a vacuum chamber, of a filler head comprising a temporary bottle stopper having vacuum and supply ducts opening through said stopper and vacuum and supply ducts communicating with the respective chambers, said filler head having a single face through which all of the several ducts open and immediately adjacent which the several liquid supply ducts are in communication with each other and the several vacuum ducts are separately in communication with each other.

56. A bottle filler comprising the combination with means providing a liquid supply chamber and a vacuum chamber, of a filler head comprising a temporary bottle stopper having vacuum and supply ducts opening through said stopper and vacuum and supply ducts communicating with the respective chambers, said filler head having a single face through which all of the several ducts open and immediately adjacent which the several liquid supply ducts are in communication with each other and the several vacuum ducts are separately in communication with each other, together with valve means for admitting air to one of said ducts, and means for maintaining the liquid supply in the supply chamber lower than said head whereby the admission of air to any of said ducts will interrupt the vacuum and the flow of liquid through said head.

57. A bottle filler comprising the combination with means providing a liquid supply chamber and a vacuum chamber, of a filler head comprising a temporary bottle stopper having vacuum and supply ducts opening through said stopper and vacuum and supply ducts communicating with the respective chambers, said filler head having a single face through which all of the several ducts open and immediately adjacent which the several liquid supply ducts are in communication with each other and the several vacuum ducts are separately in communication with each other, together with valve means for admitting air to one of said ducts, and means for maintaining the liquid supply in the supply chamber lower than

said head whereby the admission of air to any of said ducts will interrupt the vacuum and the flow of liquid through said head, said valve means comprising a closure plate adjustable on said face and adapted to be manipulated to expose the several ducts to cleansing in addition to performing the function of a valve for controlling the admission of atmospheric air as aforesaid.

58. In a vacuum filler, the combination with a supply chamber comprising a receptacle, and means for supplying liquid thereto under atmospheric pressure, of a closure for said receptacle including a vacuum chamber and a filler head disposed at a level above the level of liquid in the supply chamber and having a temporary stopper, and vacuum and supply ducts opening therethrough and provided with means affording operative communication of said ducts with the vacuum chamber and with a point in said receptacle below the level of liquid therein.

59. In a vacuum filler, the combination with a turntable means provided with bottle supports in an annular series, of a central chamber partitioned to provide liquid supply and vacuum compartments and mounted on said turntable to rotate therewith, of a centrally ported closure for the liquid compartment of said chamber removably sealed thereto, a seal for said ported closure, means for supplying liquid under atmospheric pressure through said seal to the liquid compartment of said chamber for maintaining liquid at approximately a predetermined given level in said liquid compartment, an annular series of filler heads disposed above the level of liquid in the liquid compartment and having a temporary stopper and vacuum and supply ducts opening therethrough and provided with means affording operative communication of said ducts with the vacuum compartment of said central chamber, and with the liquid compartment of said central chamber at a point below the level of the liquid therein.

60. A bottle filler comprising the combination with means providing a liquid supply chamber and a vacuum chamber, of a filler head comprising a temporary bottle stopper having vacuum and supply ducts opening through said stopper and vacuum and supply ducts communicating with the respective chambers, said filler head having a single face through which all of the several ducts open and immediately adjacent which the several liquid supply ducts are in communication with each other, a groove in the face of said head joining the several vacuum ducts, a plate applied to said face for sealing said groove and the openings of said several ducts in said face, said groove being of sufficiently restricted capacity to limit the flow between said several vacuum ducts.

61. A bottle filling machine comprising the combination with a turntable having an annular series of supports and an annular series of filler heads above the respective supports and each comprising a temporary bottle closure having first and second ports for liquid and vacuum respectively, of a supply chamber and a vacuum chamber respectively subject to atmospheric pressure and to sub-atmospheric pressure and including means whereby said chambers are substantially isolated against direct communication, whereby to maintain a pressure differential therebetween, said chambers being mounted on said turntable within said series of filler heads, a liquid supply means leading to said supply cham-

ber and provided with a float valve for maintaining a predetermined liquid level therein below the level of said heads, ducts leading upwardly from the liquid-containing portion of said vessel to the filler heads and communicating with the first ports thereof to constitute inverted U-tubes, whereof relatively long legs comprise said ducts and relatively shorter legs comprise the first ports of said heads, ducts leading from the second ports of the filler heads to the vacuum chamber, whereby the application of a receptacle to a filler head will temporarily establish communication through the ports of said filler head and the associated ducts between the supply chamber and the vacuum chamber to enable said pressure differential to fill said receptacle, and sealed means for receiving from the vacuum chamber liquid passing thereto and for returning such liquid by gravity to the supply chamber while maintaining said pressure differential.

62. A bottle filling machine comprising the combination with a turntable having an annular series of supports, and an annular series of filler heads above the respective supports and each comprising a temporary bottle closure having first and second ports for liquid and vacuum respectively, of a supply chamber and a vacuum chamber respectively subject to atmospheric pressure and to subatmospheric pressure and positioned centrally on said turntable within said series of filler heads, a liquid supply means leading to the supply chamber and provided with a float valve for maintaining a predetermined liquid level therein below the level of said heads, pipes leading from a portion of the supply chamber below said level substantially rectilinearly upwardly and outwardly to said heads and communicating with the first ports thereof to constitute inverted U-tubes, whereof the pipes and ports comprise relatively long and short legs, a second set of pipes leading from the second ports of the filler heads to the vacuum chamber, each of said filler heads having an individual supply pipe and an individual vacuum pipe, and sealed means for returning liquid by gravity to the supply chamber, the several pipes constituting skeleton frames projecting from the supply chamber upon which said heads are wholly dependent for mechanical support and for bracing, as well as for the establishment of liquid and vacuum connections.

63. A bottle filler machine comprising the combination with a turntable provided with an annular series of supports and an annular series of filler heads, each of said filler heads comprising a temporary bottle closure having liquid and vacuum ports therethrough, of a liquid supply chamber mounted centrally on said turntable and arranged to operate at atmospheric pressure, a vacuum chamber mounted on the turntable, a supply pipe leading to said supply chamber and provided with a float valve for maintaining a predetermined liquid level in said supply chamber below the level of said filler heads, duct means providing communication between the vacuum ports of said heads and the vacuum chamber, and duct means providing communication between the liquid ports of said heads and a portion of said supply chamber below the liquid level thereof, said supply chamber having a substantially free and unobstructed inner wall surface outside of which all of said last mentioned duct means is located.

ADOLPH J. LIPPOLD.

CERTIFICATE OF CORRECTION.

Patent No. 2,122,149.

June 28, 1938.

ADOLPH J. LIPPOLD.

It is hereby certified that error appears in the printed specification of the above numbered patent requiring correction as follows: Page 9, first column, lines 16 and 17, claim 15, strike out the dash, words and quotation mark "--for "in radial planes and substantially rectilinearly""; and that the said Letters Patent should be read with this correction therein that the same may conform to the record of the case in the Patent Office.

Signed and sealed this 9th day of August, A. D. 1938.

Leslie Frazer
